UNITED STATES PATENT OFFICE.

ARTHUR LIPSCHUTZ, OF ST. LOUIS, MISSOURI, ASSIGNOR OF ONE-HALF TO
HERBERT W. WOLFF, OF ST. LOUIS, MISSOURI.

BRAKE-BEAM.

SPECIFICATION forming part of Letters Patent No. 733,854, dated July 14, 1903.

Application filed March 21, 1903. Serial No. 148,959. (No model.)

To all whom it may concern:

Be it known that I, ARTHUR LIPSCHUTZ, a citizen of the United States, residing in the city of St. Louis, in the State of Missouri, have 5 invented certain new and useful Improvements in Brake-Beams, of which the following is a full, clear, and exact description, reference being had to the accompanying drawings, forming part of this specification.

10 My invention relates to the fulcrum and the manner of attaching it to the beam, the object being to provide a construction whereby a fulcrum (which in itself is inexpensive) can be readily and quickly attached to the 15 beam without the use of special tools and which when attached is securely and firmly held in position.

15 My invention consists in features of novelty hereinafter fully described, and pointed 20 out in the claims.

Figure I is a perspective view illustrative of my invention, a portion only of the body of the beam being shown. Fig. II is a perspective view of one of the filler-blocks. Fig. 25 III is a diagrammatic view showing the manner of placing the fulcrum in position on the beam. Fig. IV shows a modification.

30 Referring to the drawings, 1 represents a portion of the body of a brake-beam. This I have shown of I-beam form, although I do not wish to be limited to this particular shape for the body of the beam.

2 represents the fulcrum and the usual jaws 3, between which the brake-lever is 35 adapted to be pivoted. The head 4 of the fulcrum has an upper arm 5 and a lower arm 6, these arms being preferably formed on a slight inclination from the horizontal, as shown in Fig. III, so as to better grip the 40 filler-blocks and have less tendency to slip therefrom. The ends of the arms have in-turned lips 7, and the arms are perforated to receive a bolt or rivet 8.

9 represents filler-blocks having heads 10, 45 adapted to fit against the inner faces of the arms 5 and 6 and which occupy the space between the flange 11 of the body of the brake-beam and the inturned lips 7 of the arms. The filler-blocks have hubs 12 and wings 13,

that rest against the webs 14 of the body of 50 the brake-beam.

In attaching the fulcrum to the beam it is edged over the flange 11, as shown by dotted lines in Fig. III, and when its head 4 is brought up against the back of the flange 11 55 the filler-blocks 9 are slipped into position and the bolt or rivet 8 then applied by slipping it through the holes in the arms and through holes formed in the filler-blocks and in the web of the beam, the attachment thus 60 being made without removing the brake-shoe heads and without the use of special tools, and when the fulcrum is in position it is firmly and securely held from movement. 65

In Fig. IV I have shown a modification in which a single filler-block 9^a is used, it being illustrated in position between the fulcrum-arm 5^a and the web 14^a of the brake-beam. In this construction the second fulcrum-arm 70 6^a is made short and turned directly onto the flange 11^a of the beam instead of being continued into a length corresponding to that of the arm 5^a. The bolt 8^a passes only through the one long arm 5^a, the single filler-block, and 75 the web of the beam, thereby holding the parts firmly together without the presence of the second fulcrum-arm and filler-block between it and the web of the beam. 80

I claim as my invention—

1. A brake-beam body in combination with a fulcrum having a head provided with an arm, a filler-block fitting between the arm and the web of the beam, and a bolt or rivet passing through said arm, filler-block and web, 85 substantially as set forth.

2. A brake-beam body in combination with a fulcrum having a head provided with arms, filler-blocks fitting between the arms and the web of the beam, and a bolt or rivet passing 90 through said arms, filler-blocks and web, substantially as set forth.

3. A brake-beam body in combination with a fulcrum having inclined arms, filler-blocks located between the arms and the web of the 95 beam, and a bolt or rivet adapted to be passed through said arms, filler-blocks and web, substantially as set forth.

4. A brake-beam body in combination with a fulcrum having an arm provided with in-turned lips, filler-blocks located between the arms and the web of the beam, and a bolt or rivet adapted to pass through said arms, filler-blocks and web, substantially as set forth.
5. A brake-beam body in combination with a fulcrum having a head adapted to fit against the outer face of the beam, inwardly-extending arms projecting from the head and inclined toward each other and having lips on their inner ends, filler-blocks located between the arms and the web of the beam, and a bolt

or rivet adapted to pass through said arms, filler-blocks and web, substantially as set forth.

6. A brake-beam body in combination with a fulcrum having inwardly-extending arms, filler-blocks located between the arms and the body of the beam, and means for connecting said arms and filler-blocks together, substantially as set forth.

ARTHUR LIPSCHUTZ.
